SELECTIVE SYSTEM

Theodore A. Rich, Schenectady, N. Y., assignor
to General Electric Company, a corporation of
New York

Application January 20, 1933, Serial No. 652,681

5 Claims. (Cl. 177—353)

My invention relates to selective remote control systems and it has for one of its objects to provide means whereby a plurality of remote devices may be operated in a reliable and satisfactory manner and by means which may be more economically constructed than has heretofore been possible.

My invention has particular application in connection with the remote control of street lamps and domestic water heaters over the lines of the power distribution system from which these instrumentalities are energized. In these applications the control is effected by carrier current transmitted from a control station over the power line to actuate selectors arranged in the base of the street lamp, or at the location of the water heaters. The domestic water heaters are controlled from a central point by the power company which supplies the power in order that the water heater may be cut off during periods of peak load on the power system. It is necessary in this application that the remote control equipment be capable of selectively and reliably performing the desired operations and at the same time that its cost be a minimum.

Particularly, in the application to the control of domestic water heaters, it is further desirable not only that the system be capable of selectively turning the water heaters on and off in response to selective operations at the central station, but also that it be capable of turning all of the water heaters off non-selectively in response to some simple operation at the central station which can be easily and hastily performed. This feature is desirable in order to permit the entire water heater load to be quickly removed from the system. This is necessary at times when the load indicators at the central station indicate that the power load is approaching the value at which the line circuit breakers open, thereby to disconnect the generating system from the line and producing a general failure of power. Were the circuit breakers allowed to open, some time would be required to put the generating station back on the line, whereas the power companies are often subjected to heavy penalties for each minute of failure of power. The opening of the circuit breakers can in many instances be avoided by disconnecting a portion of the load to which the continuous supply of power is not important, such as domestic water heaters. Accordingly, it is an object of my invention to provide a system capable not only of selectively turning the load device on and off but also capable of non-selective operation to turn all of the devices off.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawing in which Fig. 1 represents the receiving selector system, Fig. 2 illustrates the transmitting means employed therewith, and Fig. 3 is a detail view of a portion of the receiver of Fig. 1.

Referring first to Fig. 2, I have indicated at 20 therein a power distribution system having a feeder 2 extending to a generating station 3 through the secondary winding of a high frequency transformer 4. The primary winding of this transformer is arranged to be connected through the contacts of a switch 5 to a high frequency alternator 6. This alternator may be one adapted to generate any desired frequency capable of being practically superposed upon the currents of the power line. A frequency of 720 cycles is commonly employed. The operating solenoid 7 of the switch 5 is arranged to be energized from a battery 8 through a switch 9. The switch 5 is ordinarily maintained in its closed position during periods when the alternator 6 is operated. The high frequency carrier is controlled by a relay 10 having contacts in series with the alternator. The operating winding of this relay is controlled by contacts 11 and a relay 12. Contacts 11 are the ordinary keying contacts of a keying device 13 such as an ordinary telephone dial. This device has a pair of off-normal contacts conventionally indicated at 14, which are arranged to close whenever the dial 13 is operated in a clockwise direction from its normal position. These contacts control the energization of the relay 12. The relay 12 is provided with a pair of contacts and armature 15 which close immediately upon energization of the winding. It is also provided with a second armature 16 having a time delay device 17 associated therewith, whereby its actuation is delayed for a predetermined interval such, for example, as 30 seconds.

When the operator desires to operate a remote device as, for example, to turn on a remote water heater, he operates the dial 13 in a clockwise direction to a desired position. Upon initial actuation of the dial 13, contacts 14 immediately close thereby energizing the windings of relays 10 and 12. Relay 10 immediately closes and supplies carrier current to the feeder. Contacts 15 of relay 12 also immediately close and complete

a holding circuit for this relay through the winding and contacts 16 thereof. This circuit is maintained for the above-mentioned interval determined by delay device 17. When the operator releases his dial, contacts 11 are opened a number of times dependent upon the position to which the dial has been operated after which the dial returns to its normal position opening contacts 14. The opening of contacts 11 causes the carrier to be interrupted to produce a predetermined number of short impulses. The interval determined by the time delay device 17, however, is substantially longer than the interval required for the dial 13 to return to its initial position with the result that following the transmission of the short impulses a longer continuous carrier impulse is transmitted until contacts 16 open, thereby deenergizing the windings of relays 12 and 10.

It will thus be seen that upon each operation of the dial, a predetermined number of short carrier impulses are supplied to the line, this impulse being followed by a long carrier impulse.

In accordance with my invention these short impulses are employed to select the remote device which is to be actuated and the long impulse is employed to actuate the selected remote device.

In case it be desired to operate all of the remote devices as, for example, in the water heater application referred to, to deenergize all the water heaters, a switch 18 may be closed. This switch causes the closing of relay 10 and thereby causes carrier current to be supplied to the line continuously so long as the switch 18 is closed. The receiving mechanism provided in accordance with my invention is adapted to respond to such a carrier impulse to operate the remote devices.

Referring now to Fig. 1, I have shown therein a load device 19 which is indicated as a lamp but which may comprise any desired device to be controlled. This device is energized through a circuit extending from the lower terminal 20 of the power line, through the load device, contacts 21 and 22, bimetallic strip 23, and conductor 24, back to the opposite side of the power line 20. Contact 22 is carried on the end of bimetallic strip 23 which when heated, by passing current through the winding 25 thereon deflects away from the contact 21 sufficiently to permit a second bimetallic strip 26 to fall behind it, thereby to prevent its return to the position shown in the drawing. The bimetallic strip 26 is also provided with a heating winding 27 and is adapted when heated to deflect upward from behind the strip 23 thereby to permit the strip 23 to return to its initial position. Thus, by selectively energizing the windings 25 and 21, the load 18 may be energized or deenergized.

One terminal of each of these windings is connected to the respective bimetallic strip which in turn is connected through conductor 24 to the upper side of the power line. The opposite terminal of these windings is connected respectively to contacts 28 and 29 of a selector 30, whereby they are selectively connected to the opposite side of the power line.

This selector 30 is operated by a magnet 31 which in turn is energized by a receiving relay 32 which is connected in the output of a carrier current receiver 33. This receiver is adapted to respond to carrier current received in a tuned circuit 35 connected across the power line.

The selector 30 comprises a disk 36 fixed upon a shaft 37 and carrying a contact member 38.

Upon rotation of the shaft 37 and disk 36 the contact member 38 is carried into engagement with the different contacts 28, 29. The shaft 37 is actuated by means of a ratchet 39 and pawl 40. The pawl 40 is actuated by the armature 41 of the electromagnet 31. This armature is pivoted at the point 42 and is biased by means of a spring 43 away from the magnet and thereby retains the pawl 40 in its left-hand position. The pawl 40 is forced against the teeth of the ratchet by means of a spring member 44 and detent 58. The left end of the detent 58 is bowed, the bowed portion being pivoted upon the end of spring 44 which is mounted on an arm 47 of the frame of the apparatus. The left end of the bow rests against the teeth of the ratchet, whereas the right end of the bow supports the pawl 40 and causes it to bear against the ratchet under bias of the spring 44. The contact 45 when in the position shown in the drawing makes engagement with the insulated contact 46. When the pawl 40 is actuated to the right, however, by energization of the magnet 31, the contact 45 is retained in its closed position until the pawl 40 is forced upward under influence of spring 44 against the next tooth of the ratchet. When this occurs the detent 58 is rotated about its pivot in a counter-clockwise direction, and it thereby disengages the contacts 45 and 46.

The contacts 45 and 46 are included in a re-setting circuit for the selector, this circuit extending from the upper conductor of the power line 20 through the winding 31, conductor 48, shaft 37, ratchet 39, contacts 45 and 46, and resistance 49, to the opposite side of the power line. Thus, whenever the contact 45 is in the position shown in the drawing, current flows in the above-traced circuit. This current is insufficient to energize the magnet 31. The resistance 49, however, is the heating unit of a bimetallic strip 50 which when deflected under the influence of heat from resistance 49 short circuits that resistance. Sufficient current then flows in the magnet 31 to cause operation of the selector. The magnet 31 attracts its armature, thereby causing the pawl 40 to be moved to the right until it is forced upward under the influence of biasing spring 44 against the next adjacent tooth of the selector. When this occurs, contact 45 leaves engagement with contact 46 and interrupts the circuit of the magnet. Spring 43 then pulls the armature 41 away from the magnet and actuates the pawl 40 toward the left, thereby operating the ratchet through the space of one tooth. This operation repeats itself until a member 51 of the disk 36 engages the projection 52. This latter projection is a portion of a member 53 which is supported at its upper end from the frame of the apparatus being insulated therefrom and has a lower arm 54 which is adapted to be operated beneath detent 58 when the latter is in its upper position. That is, engagement of member 51 with projection 52 forces the arm 54 underneath detent 58, thereby to prevent contact 45 from engaging with contact 46 upon the next deenergization of the magnet 31. This in turn permanently deenergizes the magnet 31 and causes the disk 36 to be maintained in the position in which the member 51 engages the contact 52. This is the normal position of the apparatus.

Now let us suppose that the operator at the central station desires to disconnect the load 19 from the power line. He will operate his dial 13 to the position corresponding to the desired

operation, thereby supplying to the line 20 a number of short carrier impulses followed by a long impulse. Each of these impulses causes operation of the relay 32 which in turn energizes the magnet 31 through an obvious circuit in accordance with the impulses. The selector is therefore actuated by its ratchet and pawl mechanism through a number of steps corresponding to the number of short impulses received. The number of short impulses will be such that the selector is so operated that contact 38 engages contact 28, thereby completing a circuit for the subsequent long impulse. This circuit extends from the lower side of the power line through the contacts of relay 32, conductor 48, shaft 37, disk 36, contacts 38 and 28, winding 25, bimetallic strip 23, and conductor 24, to the opposite side of the power line. The long impulse is of such duration that the bimetallic strip 23 will be sufficiently heated to cause it to deflect away from the contact 21. It is then retained in its deflected position by strip 26 falling behind it. During the long impulse the magnet 31 is maintained continuously energized. The pawl 40 is therefore in its right-hand position and the contact 45 in its open position. Resistance 49 is therefore cold. Upon termination of the long impulse, the magnet 31 becomes deenergized and the contact 45 is at once operated into engagement with contact 46, thereby completing the above-traced circuit for resistance 49. After a short interval, strip 50 short circuits resistance 49 and thereby causes the selector to be actuated to its normal position, as previously described.

Now, if the operator desires to energize the load 19, he will operate the dial 13 to a different position thereby transmitting a different number of short impulses to actuate the contact 38 into engagement with contact 29, whereupon the heating unit 27 is energized during the period of the subsequent long impulse. This in turn causes the bimetallic strip 26 to deflect upward sufficiently to release the strip 23, which in turn again closes the load circuit. After termination of the long impulse the selector again returns to its normal position.

It will now be understood that a selector of the type described is employed in connection with each of the water heaters to be controlled. These selectors may be arranged to turn all the water heaters on in response to a particular code combination of impulses and to turn them all off in response to a different code combination of impulses, or the different selectors may be arranged to effect these operations in response to codes different from those to which other selectors respond, as desired. If desired, additional pairs of contacts 28, 29 may be provided on any selector whereby it may be responsive to different codes to control additional load devices. It is desired, however, that all of the selectors be adapted to respond to a common signal transmitted from the central station to turn their respective water heaters off. For this purpose, a circuit is provided which extends from the lower side of the power line 20 through the contacts of relay 32, conductor 48, shaft 37, disk 36, when in its normal position, members 51 and 52, conductor 55, contact 28, heating winding 25, bimetallic strip 23, and conductor 24, to the other side of the line. This circuit is completed whenever relay 32 is energized and selector 36 is in its normal position. Thus, if the operator at the central station holds the switch 18 in its closed

position thereby sending out a long impulse, the unit 25 is energized for a sufficient period to cause the load 19 to be deenergized.

The particular mechanical construction and arrangement of the pawl 40, ratchet 39, and detent 58 is of importance in the operation of the selector described, for the reason that it assures positive operation of the selector and at the same time avoids overrunning of the ratchet. It will be noticed that the pawl is operated to the right and left in substantially the plane of the pawl and that the contact 45 is held in engagement with contact 46 which is supported by, but insulated from, the supporting arm 47 until the pawl in its movement to the right slips off the edge of the ratchet tooth against which it is pressed by the detent 58 under the bias of spring 44. Contacts 45 and 46 then separate, deenergizing magnet 31 which allows spring 43 to return the pawl to its extreme left-hand position. This left-hand movement of the pawl is limited by the edge 57 of the pawl engaging shaft 37. The ratchet is thereby rotated clockwise an amount equal to one tooth, further rotation being prevented by the extension 56 of the ratchet engaging the shaft. Just prior to the ratchet reaching this position the detent 58 drops to the root of the next tooth, and in so doing the detent rotates clockwise to close the contacts 45, 46 to reenergize magnet 31.

While I have shown a particular embodiment of my invention, it will of course be understood that I do not wish to be limited thereto since many modifications may be made both in the circuit arrangement and the instrumentalities employed. I, of course, contemplate by the appended claims to cover any such modifications as fall within the true spirit and scope of my invention.

What I claim as new and desire to secure by Letters Patent of the United States is:

1. The combination, in a selector system, a control device having a plurality of actuating members, a selector having a normal position and a plurality of other positions, said actuating members being connected respectively to said other positions of said selector, means responsive to coded impulses to operate said selector from said normal position to any of said other positions, means to energize the selected actuating member through said selector in the selected other position, and means to energize a predetermined one of said actuating members through said selector when said selector is in said normal position.

2. The combination, in a remote control system, a plurality of devices to be actuated, a receiving relay, a selector having a normal position and a plurality of other positions corresponding to said devices to be actuated, means responsive to said receiving relay to operate said selector to any one of said other positions, means responsive to said receiving relay to energize the selected device when said selector is in the position corresponding thereto, means responsive to said receiving relay to energize said one of said devices when said selector is in said normal position, and means to prevent actuation of said one of said devices in response to actuation of said receiving relay to operate said selector to one of said other positions.

3. The combination, in a remote control system, a plurality of devices to be actuated, a receiving relay, a selector having a normal position and a plurality of other positions corresponding

to said devices to be actuated, means responsive to said receiving relay to operate said selector to any one of said other positions, means responsive to said receiving relay to energize the selected device when said selector is in the position corresponding thereto, and means responsive to said receiving relay to energize one of said devices when said selector is in said normal position, said last means being ineffective to actuate said one device upon operation of said selector to any of said other positions.

4. In combination, a load contact, means to operate said contact to closed position, means to operate said contact to open position, means operable from a control point to transmit either a long impulse or combinations of impulses, each combination comprising a plurality of short impulses followed by a long impulse, means responsive to said short impulses to select a predetermined one of said operating means, means responsive to the long impulse following said short impulses to actuate the operating means selected by said last means, and means responsive to the first-mentioned long impulse to operate one of said operating means, whereby said load contact may be operated to one position in response to said first-mentioned long impulse, and may be

selectively operated to either position in response to said combination of impulses.

5. The combination in a remote control system, a control member arranged to be operated between two positions, a plurality of devices to be actuated thereby to operate said member between said two positions, each of said devices being slow acting, a selector having a normal position and a plurality of other positions corresponding to said devices to be actuated, means responsive to a received combination of short impulses to actuate said selector to any one of said positions, means subsequently responsive to a received impulse of long duration to energize the device corresponding to the position to which said selector has been actuated for a period determined by the duration of said received long impulse thereby to operate said control member from one position to its second position, means automatically operable after said long impulse is terminated to actuate said selector to said normal position, and means for energizing one of said devices when said selector is in said normal position thereby to operate said control member to a predetermined one of its two operating positions.

THEODORE A. RICH.
